(57) **CLAIM**

The ornamental design for a microphone, as shown and described.

DESCRIPTION

FIG. 1 is a front, left, top side perspective view of a microphone of the claimed design;

FIG. 2 is a rear, right, top side perspective view of FIG. 1; FIG. 3 is a rear, left, bottom side perspective view of FIG. 1;

FIG. 4 is a front elevational view of FIG. 1;

FIG. 5 is a rear elevational view of FIG. 1;

FIG. 6 is a left side elevational view of FIG. 1;

FIG. 7 is a right side elevational view of FIG. 1;

FIG. 8 is a top plan view of FIG. 1;

FIG. 9 is a bottom plan view of FIG. 1;

FIG. 10 is a rear, right, top side perspective view of FIG. 1, showing the microphone in an environment of use;

FIG. 11 is a front, left, top side perspective view of FIG. 10; and,

FIG. 12 is a rear, left, top side perspective view of FIG. 1, showing the microphone in another environment of use.

The dash-dot broken lines shown in the drawings depict the bounds of the claim that form no part of the claimed design. The evenly dashed broken lines shown in FIG. 10-12 showing a stand depicts environmental structure that forms no part of the claimed design. All other evenly dashed broken lines shown in the drawings depict portions of the microphone that form no part of the claimed design.

1 Claim, 12 Drawing Sheets
